(57) **CLAIM**

The ornamental design for an electric contact, as shown and described.

DESCRIPTION

FIG. 1 is a top plan view;
FIG. 2 is a front elevation;
FIG. 3 is a bottom plan view;
FIG. 4 is a right-side elevation;
FIG. 5 is a rear elevation;
FIG. 6 is a perspective view; and,
FIG. 7 is an auxiliary figure showing a cross-sectional view taken along the longitudinal center of the contact shown in use, wherein the subject article (i.e., the electric contact) 1 is secured on the insulated cord 2 and brought into an electric connection with a conductor 3 coated with an insulating mantle 4, through the latter.
The broken lines showing the insulated cord, the conductor and insulating mantle in FIG. 7 are included for the purpose of illustrating environmental structure only and form no part of the claimed design.
